HOLDER FOR CUPS, CANS, AND SIMILAR ARTICLES

Harold Grinspoon, Springfield, Mass.

Application November 29, 1954, Serial No. 471,553

9 Claims. (Cl. 206—65)

This invention relates to a holder for articles such as filled paper food containers of the cup type, and small cans of food or other materials, and pertains more particularly to the type of folding holder made of paperboard or similar material, which can be set up to hold a group of stacked or aligned cups or cans so that they can be handled as a unit.

The ordinary type of cup in which ice-cream and similar foods are packed is of generally circular shape and has a recessed bottom and top cover, leaving projecting rims around the top and bottom. The top rim, and sometimes the bottom rim, is finished with a rolled edge or bead, which overhangs the outside of the container wall.

In large self-service markets, there would be a considerable loss from pilferage, as customers can eat ice-cream and dispose of the cup before reaching the check-out counter. For this reason, such markets do not find it profitable to carry ice-cream in individual cups, and a package which will hold a number of cups as a unit, and will be proof against pilferage, presents new marketing possibilities.

Furthermore, it is often desirable to package as a unit several different kinds of foods, representing the ingredients of a particular dish, for example, a package for a spaghetti "dinner" would consist of a can of sauce and packages or bags of the dry ingredients, such as uncooked spaghetti and cheese, which are to be combined when the meal is prepared.

The general object of this invention is to provide an inexpensive holder, suitable for the purposes discussed above, having a locking device which engages the rim of a cup or can to lock the article securely in place. Other objects are to produce a holder which, in partly assembled condition, may be folded flat for shipment and storage, and which can be readily set up and packed by hand, so that it is suitable for use by dairies and small food packing concerns which may or may not be equipped with automatic packaging machinery. Other advantages of the holder will be apparent from the description which follows:

In the drawings illustrating the invention:

Fig. 1 is a perspective view of a holder constructed according to the invention;

Fig. 2 is a longitudinal cross-section, somewhat enlarged, of the holder of Fig. 1;

Fig. 3 is a plan view of the empty holder partly assembled;

Fig. 4 is a plan view of the blank from which the holder is made;

Fig. 5 is a plan view of a modified form of holder, partly assembled;

Fig. 6 is an enlarged cross-section, partly broken away, of the holder of Fig. 5 as it would appear when filled;

Fig. 7 is a longitudinal cross-section of a modified form of holder;

Fig. 7a is a perspective view of the holder of Fig. 7 shown empty;

2

Fig. 8 is a perspective view of another modification of the holder;

Fig. 9 is a longitudinal cross-section, somewhat enlarged, of the holder of Fig. 8;

Fig. 10 is a plan view of the empty holder of Fig. 8 in partly assembled form;

Fig. 11 is a plan view of another modification of the holder, in partly assembled form;

Fig. 12 is a longitudinal cross-section, partly broken away, of the holder of Fig. 11 as it would appear when filled;

Fig. 13 is a longitudinal cross-section, partly broken away, of another modification of the holder;

Fig. 14 is a plan view of the empty holder of Fig. 13 in partly assembled condition; and

Fig. 15 is a plan view of the blank from which the holder of Fig. 13 is made.

The form of holder shown in Figs. 1 through 4 is intended for two stacks of paper cups 20 of the usual type having recessed ends and projecting top and bottom rims 21 and 22. The blank for making the holder is in the form of a strip preferably divided by scored fold lines into a top wall 23, side walls 24 and 25, a bottom wall 26 and a joining tab 27. As the first step is assembling the holder, the joining tab, which may be covered with adhesive, is pasted to the free end of side wall 25 to form a continuous band. The holder when thus assembled appears as in Fig. 3.

A pair of flaps 33 and 34 are cut out of the top wall 30 leaving a central strip 35. Slots 36 and 37 may also be cut out of the top wall in the region between the flaps and the edges of the holder. A similar pair of flaps 38 and 39 are cut in the bottom wall 26 leaving an opening 40.

As the holder is intended for tapered articles the top wall 23 is wider than the bottom wall 26. It is therefore apparent that the dimension designated A between fold lines 30 and 28 will be longer than the sum of the dimensions B and C and that the holder will not fold flat when assembled as in Fig. 3 if only the usual corner fold lines are used. For this reason an extra fold line 32 is provided which is spaced from line 30 by one-half the difference between the widths of the top and bottom walls. When the blank is assembled into a band, line 32 will be equidistant from line 28 in either direction along the band. The band will therefore fold flat on lines 32 and 28.

When the cups are inserted into the holder, the central strap 35 is pressed downward and engages under the outside of the beads 21a of the upper cups, as shown in Fig. 2. The flaps 33 and 34 are also compressed down and engage inside the upper rims 21 of the two uppermost cups. The flaps, if scored, will tend to be self-locking, as they tend to drop inside the cup rim.

The flaps 38 and 39 are similarly pressed upward inside the bottom rims 22 of the lowermost cups. The cups are thus locked firmly in the holder against movement in either direction. One or more packages of spoons 41 may be inserted through the slots 36 and 37. Preferably, the side walls are slit part way down from the edges of strap 35, to provide a little extra length for the strap, and scored along lines 35a and 35b to facilitate bending the strap down. The strap may also have several central score lines 35c to facilitate the downward bending.

When the cups are thus assembled in the holder, it is difficult, if not impossible, to remove a single cup without tearing the holder. Due to the fact that the cups are tapered, the strap forces the upper cups outward against the top rims, of the lower cups, giving the unit a smoother, more symmetrical appearance. The strap, while providing a tight lock for the cups also

separates them, giving the enclosed product an appearance of greater bulk. The whole group is thus held together as a unit which can be conveniently and economically handled and sold as a single package, and the units can be stacked firmly one on top of the other.

The form of holder shown in Figs. 5 and 6 is very similar to that shown in Figs. 1 through 4 except that the flaps 42 and 43 of the top wall 44 are cut with projecting tabs or teeth 45 and 46, respectively. The central strap 47 will have notches corresponding to the teeth 45 and 46 and intervening tab portions 48 in the spaces between the teeth. When the flaps are inserted the tabs 45 and 46 are jammed against the inside of the cup rim and tend to bend upward, as shown in Fig. 6. Figs. 5 and 6 also illustrate an important feature which may be employed to equal advantage in connection with plain flaps such as flaps 38 and 39 of Figs. 1-4. Flap 43 has a hinge line 49 along its base and a second hinge line 50 spaced further outward along the flap, leaving an intermediate portion 51. When the flap is inserted in the cup rim the flap is bent downward along line 49 and outward along line 50 so that the intermediate portion 51 extends downward toward the top of the cup and the remaining part of the flap lies substantially flat against the top. Furthermore, the side margins 51a and 51b are cut on a radius greater than that of the inside of the cup rim, so that the intermediate portion 51 is wider, in the direction transverse to the flap than the inside of the cup rim. Dotted lines 20a and 20b in Fig. 5 indicate the inner and outer radii, respectively of a cup rim. Side margins 51a and 51b will therefore jam inside the rim and tend to bend toward the free end of the flap, when the flap is inserted in the cup rim, as shown in Fig. 6, thus holding the intermediate portion tightly in place and, in turn, holding the remainder of the flap down. If the cup is pulled toward the open end of the holder, the intermediate portion of the flap is driven into an increasingly narrow space inside the cup rim, and this wedging action tends to jam the intermediate portion more tightly inside the rim and hold the remainder of the flap more tightly against the cup cover. Flap 42 is constructed in the same manner as flap 43, and the holder has a similar pair of flaps on the bottom which engage inside the bottom rim of the cups.

The holder shown in Figs. 8, 9 and 10 is suitable for packaging two stacks of paper cups. This holder consists of a continuous band divided by fold lines into a top wall 65, side walls 66 and 67, and a bottom wall 68. A pair of flaps 69 and 70 are connected to the ends of the top wall. The top wall also has openings 71 and 72 with curved edges suitable for clearing the ends of the flaps when the latter are bent inward. Between these openings is a central strap portion, 73. To fill the holder, as shown in Fig. 9, the strap portion 73 is pushed down to engage the outside of the upper rims of the uppermost cups in the stack, and the flaps 69 and 70 are then bent inward to engage the inside of the rims. The bottom wall 68 has a similar pair of flaps 75 and 76 which engage inside the bottom rims of the cups. The cups are thus secured against displacement in either direction in the holder. Packages of spoons 74 are placed over the top of the holder and have their ends tucked under the margins of the top strap to either side of the openings 71 and 72. The spoons which may be inserted before or after the cups, are thus securely held and assist in locking down the flaps 69 and 70 so that the whole assembly is tightly held together.

Due to inaccuracies or manufacturing tolerances the diameter of the flaps 69 and 70 may turn out to be slightly greater than the inside diameter of the openings 71 and 72. If these flaps are cut off short enough so that when they are forced upward during insertion of the cups they do not interfere with strap 73, particularly at slits 73, this enables the strap to fit more readily under the outside rims of the uppermost cups and the

flaps will drop down more readily inside the rims of the uppermost cups. If the curved side edges of the flaps fit fairly tight inside the rims, and the areas of contact between the flaps and the rims extend inward beyond the center of the cups, it is apparent that the flaps will lock the cups against removal in outward direction even though the tips of the flaps are cut off.

The modification shown in Fig. 7 is intended for a "combination" package, for example, for combining a single can of sauce with the dry ingredients for making a spaghetti dish. The can 53 which has recessed ends surrounded by the usual beads 54 and 55 is placed across the open end of a box-like carton 56. This carton is made like an ordinary box except that two of the walls 57 and 58 are provided with flaps 59 and 60 which may be very similar in form to the flaps shown in Figs. 7, 8 and 9. These flaps engage inside the beads 54 and 55 respectively. The walls 57 and 58 have openings with margins 61 and 62 which engage under the beads on the outside of the can. As in Figs. 8, 9 and 10, these openings may communicate with slits, for example, 61a and 62a which extend part way down the sides of the box. The can is thus securely held in place across the open end of the box and serves as a closure for the box so that the remainder of the box may be used to contain dry ingredient packages, for example, in a bag 63.

The holder shown in Figs. 11 and 12 is designed for holding two stacks of tapered cups in slightly tilted arrangement. This holder also consists of a continuous band having a top wall 78, side walls 79 and 80, and a bottom wall 81. A pair of flaps 82 and 83 are cut out of the top wall, leaving a central strap portion 88. Flap 82 has two score lines 84 and 85, and, between these score lines the flap is cut to a larger radius than that of the cup rim, so that the margins 82a of this area tend to jam inside the rim, as shown in Fig. 12. Flap 83, similarly, has score lines 86 and 87 and margins 83a which tend to jam inside of the cup rim.

As the cups are tilted, when placed in this holder, the bottom edges of the two stacks touch each other, so that the bottoms are held against inward displacement. The middle strap 88 locks under the upper rims of the cups and holds the upper part of the top cups tightly locked in the inward direction. In this holder, as well as in other modifications, adjacent pairs of flaps 100 and 101 and 105 and 106, on either side of a slit, may be cut in one of the side walls to allow for insertion of spoons. After the spoons are inserted, these flaps spring back and close the opening so that the spoons cannot drop out.

A second pair of flaps 107 and 108, similar to flaps 69 and 70 in Fig. 10, for example, but somewhat shorter may be provided along the free edges of top wall 78 and may be bent down inside the top rims of the cups to block the space under flaps 82 and 83, and thus prevent anyone from reaching under the band with his fingers to loosen portions 82a or 83a by pushing those portions up.

Another feature of this modification, which may be applied to other versions of the holder, is that the side wall 79 is cut away near its upper edge along the dotted line 79b, so that the slits 82b go through only one thickness of paper at this point. The overlapping tab 104 may be cut on the same contour, so as to minimize waste of paper in cutting successive blanks. This tab may also serve as a thumb grip for opening the holder.

The holder of Figs. 13, 14 and 15 is very similar to that shown in Figs. 8, 9 and 10 except that the bottom flaps 89 and 90 are cut with a number of serrated tabs 91 and 92, respectively, around their margins. The openings 93 and 94 are cut with notches 95 and 96, respectively, disposed to admit the tabs on flaps 89 and 90 when the latter are folded in. The flaps 89 and 90 lock in place inside the top rims of the uppermost cups and the central strap portion 97 lies between the two top cups and engages under the beads in the manner previously described.

In all of the holders here described the top and bottom walls are slotted substantially to their edges at the corners of the cuts defining the openings. The slits part way down the side walls so as to free the central strap portion and allow it to be bent down to seal all around under the bead of the cups. For example, the openings 93 and 94 in the holder just described communicate with slits 93 and 99 which extend substantially to the edges of the top wall and part way down the side walls. Any of the holders which are intended for tapered articles may also have an extra fold line similar to fold line 32 in Fig. 4 so that the partly assembled holder may be folded flat for storage.

What is claimed is:

1. A holder, of resilient paperboard or similar material, for packaging a group of articles including an article having a recessed end surrounded by a projecting rim, comprising: a body having top, bottom, and side walls; one of said walls overlying said end; a flap connected to the wall overlying said end, seated against the inside of a portion of said rim and locking the article against displacement in one direction; an opening in said overlying wall adapted to admit said portion of said rim, the holder having slits extending from said opening transversely across said overlying wall and part way down the adjacent walls; and a marginal portion of said overlying wall adjacent said opening seating edgewise against the outside of said portion of said rim and locking the article against displacement in the opposite direction.

2. A holder, of resilient paperboard or similar material, for packaging a row of articles having recessed tops surrounded by projecting rims comprising: a continuous band passing around the row, having a top wall overlying the tops of said articles; a pair of flaps connected to said top wall, each of said flaps being seated against a portion of the inside of the rims of one of the end articles in the row and locking said end articles against outward displacement in the holder; a pair of openings in said top wall adapted to admit a portion of the rims of the end articles; marginal portions of said top wall adjacent said openings seating against the outside of a portion of the rims of said end articles and locking the latter against inward displacement in the holder; and a pair of slots in the regions of the top wall overlying said end articles for receiving a substantially flat member which, when it is in place, tends to hold said flaps and said marginal portions in their respective seated positions.

3. A holder as described in claim 1, said flap and opening being both formed by a single cut in the wall overlying said end.

4. A holder as described in claim 1, said flap comprising an extension of said wall and being folded inwardly toward the same.

5. A holder, of resilient paperboard or similar material, for packaging a group of articles, including an article having a recessed end surrounded by a projecting rim, comprising: a body having top, bottom and side walls; an opening in said top wall receiving, a portion of said rim, said top wall having a marginal portion engaging the outside of said rim to hold the article against displacement in one direction, said holder having a pair of slits communicating with said opening and extending across said top wall, each slit extending part way down one of said side walls; and a flap connected to said top wall, having a first hinge line along its base and a second hinge line spaced from the first, the two hinge lines

defining an intermediate portion, said flap being folded toward said end along said first hinge line, and toward said marginal portion along said second hinge line and engaging the inside of said rim to lock said article against displacement in the opposite direction, and said intermediate portion being wider than the article at its point of engagement with the rim, so as to jam inside the rim.

6. A holder as described in claim 1, the flap having tabs around its free end, and the margin having notches to permit passage of the tabs through the opening.

7. A holder of resilient paperboard or similar material, for packaging a row of generally circular articles having recessed tops surrounded by projecting rims, comprising: a continuous band passing around the row, having a top wall overlying said tops and side walls connected to said top wall; and a pair of substantially semi-circular cuts in said top wall defining flaps adjacent the ends of the band, each of said flaps seating against the inside of a region of the rim of one of the end articles and locking the same against outward displacement in the holder; two pairs of slits, each communicating with one of said cuts and extending part way down either side wall, said cuts and slits defining a central strap having marginal portions engaging a portion of the outside of the rims of the end articles and locking the same against inward displacement in the holder.

8. A holder, of resilient paperboard or similar material, for packing a group of articles including an article having a recessed top and bottom surrounded, respectively, by projecting top and bottom beads, comprising: a box having a top wall, a bottom wall, side walls, an end wall an open end, the circular article being disposed in said open end; a flap attached to said top wall engaging a region of the inside of said top bead and locking the article against outward displacement in the holder; an opening in said wall admitting a portion of said top bead; and a margin around said opening engaging a portion of said top bead and locking the article against inward displacement in the holder, said bottom wall having a flap, and a margin similarly engaging said bottom bead.

9. A holder, of resilient paperboard or similar material, for packaging a group of articles including a circular article having a recessed top surrounded by a projecting rim, comprising: a continuous band having a top wall overlying said top, a flap attached to said top wall and extending therefrom, said flap being folded inward and engaging a region of the inside of said rim and locking the article against outward displacement in the holder; and an opening in said top wall having a straight margin overlying said top, and a curved margin seated against the outside of a portion of said rim, and locking the article against inward displacement in the holder.
